(57) **CLAIM**

What is claimed is the ornamental design for a cell phone and
ipod bag with lobster claw hook, as shown and described.

DESCRIPTION

FIG. 1 is a perspective view of a cell phone and ipod bag with
lobster claw hook, illustrating a first embodiment of the new
design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken line showing stitching is part of the claimed
design.
